CLAIM

The ornamental design for a pivot bin, as shown and described.

DESCRIPTION

FIG. 1 is a bottom perspective view of a pivot bin showing our present invention;

FIG. 2 is a front elevational view of the present invention shown in FIG. 1;

FIG. 3 is a rear elevational view of the present invention shown in FIG. 1;

FIG. 4 is a left side elevational view of the present invention shown in FIG. 1, the right side elevational view being a mirror image thereof; and,

FIG. 5 is a bottom plan view of the present invention shown in FIG. 1.

1 Claim, 5 Drawing Sheets
